(57) **CLAIM**

The ornamental design for an electronic magnifier for smartphone, as shown and described.

DESCRIPTION

FIG. 1 is a perspective view of an electronic magnifier for smartphone showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof;

FIG. 8 is a perspective view thereof when not in use; and,

FIG. 9 is a perspective view thereof when in use with a smartphone.

The broken line showing of the smartphone is for the purpose of illustrating the environmental structure and forms no part of the claimed design.

1 Claim, 9 Drawing Sheets
